HEDDLE FRAME

Filed Nov. 16, 1928

Fig. 1.

UNITED STATES PATENT OFFICE

JOHN JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA

HEDDLE FRAME

Application filed November 16, 1928. Serial No. 319,777.

My invention relates to heddle frames for looms, and it relates more particularly to that type of heddle frame in which individual warp controlling heddles are mounted on supporting bars carried by the frame.

The principal object of my present invention is to provide a heddle frame of greatly improved construction, in which the end members, as well as the top and bottom rails, are made of relatively thin strips of wood or similar material, reinforced by metallic strips, and in which the end members will be more efficiently secured to the top and bottom rails.

A further object of my invention is to provide improved means for securing the heddle supporting bars in place, which will be inexpensive yet efficient, which will not be likely to become detached in use, and which may be readily removed for replacement when broken.

The nature and characteristic features of my invention will be more readily understood from the following description, taken in connection with the accompanying drawings forming part hereof, in which:

Figure 1 is a side elevation of a heddle frame embodying the main features of my present invention;

Fig. 2 is a fragmentary detail view enlarged, partly in section, of a corner portion of the heddle frame shown in Fig. 1, the same illustrating more clearly the details of construction and arrangement of the parts constituting the present invention;

Fig. 3 is an end elevation of the portion of the structure shown in Fig. 2;

Fig. 4 is a vertical section taken approximately on the line 4-4 of Fig. 2; and

Fig. 5 is an elevational view of one of the hook members used for securing the heddle supporting bars in place in the frame.

Referring to the drawings, the heddle frame proper may comprise top and bottom rails 6 and end members 7, all of which are preferably made of relatively thin strips of wood.

The end members 7 may be reinforced by metallic strips 8 on the inner faces of the

members 7, and by similar strips 9 on the outer faces of said members 7.

The end portions of the reinforcing strips 8 are bent over at right angles and extend along the inner faces of the top and bottom rails 6, as at 10, being secured thereto by screws 11 extending into the rails 6.

The outer reinforcing strips 9 extend over the end portions of the top and bottom rails 6, and are bent over, as at 12, and secured to the outer faces of the top and bottom rails 6 by screws 13.

Rivets 14, extending at various places through the wooden end members 7, secure the reinforcing strips 8 and 9 thereto and to each other.

The heddle supporting bars 15, with the heddles 16 arranged thereon in the usual manner, are mounted in the frame by having their end portions extending through slots 17 provided in the end members 7, and through complementary slots 18 and 19 provided in the reinforcing strips 8 and 9, respectively.

The ends of the heddle supporting bars 15 project beyond the outer reinforcing strips 9, and these end portions of the heddle supporting bars are apertured as at 20, for engagement by the securing devices.

Each of the securing devices comprises a member 21, shown in detached detail in Fig. 5 of the drawings, and preferably made of spring steel wire. One end of the member 21 has a bent over hook-like extension 22, which is adapted to engage the aperture 20 in the end of the heddle supporting bar 15.

The other end of the securing device 21 is also provided with a bent over extension 23, which is adapted to be positioned in a transverse hole in the end member 7, being held therein by frictional engagement.

Adjacent the bent over extension 23, the body portion of the securing device 21 is provided with an inset portion 24, which is adapted to be seated in a slot 25 provided in the outer reinforcing strip 9.

Between the inset portion 24 and the bent over extension 23 is a semi-circular loop 26, which extends beyond the outer surface of the reinforcing member 9, for a purpose to be presently explained.

In mounting the heddles in the frame, after the same are properly arranged upon the heddle supporting bars, the heddle supporting bars are then inserted in the slots 17 in the end member 7, also passing through the complementary slots 18 and 19 of the reinforcing strips 8 and 9.

The extension 22 of the securing members are then sprung into engagement with the apertures 20 provided in the ends of the heddle supporting bars 15, thereby maintaining the same against displacement.

It may here be noted that the engagement of the inset portion 24 of the securing device 21 with the slot 25 in the reinforcing strip 9, will serve to prevent the securing device 21 from rotating about the extension 23 as an axis, thereby preventing accidental disengagement of the hook-like extension 22 from the aperture 20 in the heddle supporting bar.

It will also be noted that by reason of the extension of the semi-circular loop 26 of the securing device beyond the outer face of the reinforcing strip 9, there is provided a ready means for removal of the extension 23 of the securing device from the strip 7 in the event of breakage of the securing device.

It will be seen that there is thus provided a heddle frame of improved construction, in which likelihood of disengagement of the securing means from the heddle supporting bars is reduced to a minimum, and in which the replacement of a broken securing device is greatly facilitated, and damage to the frame in the removal of the broken part therefrom is eliminated.

Having thus described the nature and characteristic features of my invention, what I claim as new and desire to secure by Letters Patent, is:

1. A heddle frame comprising top and bottom rails and end members; metallic reinforcing strips on the inner and outer faces of said end members, the ends of said reinforcing strips being bent over and secured to the top and bottom rails; heddle supporting bars mounted in said frame extending through slots in the end members and in the reinforcing strips, said heddle supporting bars having their ends projecting beyond the outer reinforcing strips; securing devices each adapted to engage one of said projecting end portions of a heddle supporting bar and comprising a member made of spring wire having one end thereof engaging the end of the heddle supporting bar, and having the other end thereof bent over and extending into the end member; the securing member having an inset portion adjacent the portion which extends into the end member of the frame, the outer reinforcing strip having a slot in which said inset portion is seated, and the securing member having a loop adjacent the portion which extends into the end member, said loop extending outwardly beyond the transverse

plane of the adjacent portion of the securing member and beyond the outer face of the outer reinforcing strip.

2. A heddle frame comprising top and bottom rails and end members; metallic reinforcing strips on the inner and outer faces of said end members, the ends of said reinforcing strips being bent over and secured to the top and bottom rails; heddle supporting bars mounted in said frame extending through slots in the end members and in the reinforcing strips, said heddle supporting bars having their ends projecting beyond the outer reinforcing strips and having apertures provided in said projecting portions; securing devices each adapted to engage one of said projecting end portions of a heddle supporting bar and comprising a member made of spring wire having one end thereof bent over and engaging the aperture in the end of the heddle supporting bar, and having the other end thereof bent over and extending into the end member; the securing member having an inset portion adjacent the portion which extends into the end member of the frame, the outer reinforcing strip having a slot in which said inset portion is seated, and the securing member having a loop adjacent the portion which extends into the end member, said loop extending outwardly beyond the outer face of the transverse plane of the adjacent portion of the securing member and beyond the outer reinforcing strip.

In testimony whereof, I have hereunto signed my name.

JOHN JACOB KAUFMANN.

CERTIFICATE OF CORRECTION.

Patent No. 1,783,794.

Granted December 2, 1930, to

JOHN JACOB KAUFMANN.

It is hereby certified that error appears in the printed specification of the above numbered patent requiring correction as follows: Page 2, line 95, claim 2, strike out the words "the outer face of" and insert the same to follow "beyond" in line 97, of same claim; and that the said Letters Patent should be read with this correction that the same may conform to the record of the case in the Patent Office.

Signed and sealed this 13th day of January, A. D. 1931.

(Seal)

**M. J. Moore,
Acting Commissioner of Patents.**
